UNITED STATES PATENT OFFICE.

OSKAR OLSEN, OF BROOKLYN, NEW YORK.

DEVICE FOR HANGING FORMS FROM STRUCTURAL STEEL.

Application filed August 21, 1922. Serial No. 180,595.

This invention relates to a device constructed for hanging forms from structural steel, and it has for its object to produce an apparatus that will prove easy to apply and adjust, very solid and durable, and which will prove a great factor in saving materials, such as boards, etc., used in connection therewith, besides being through its simplicity of operation a great time saving device.

With the above and other objects in view, this invention consists of the novel features of construction, combination and arrangements of parts, hereinafter fully described, claimed, and illustrated in the accompanying drawings forming parts of this specification, and in which similar characters of reference indicate corresponding parts in all views, and in which:

20 Figure 1 is a plan view of my invention in actual use; Fig. 2 is a similar, but modified view; Fig. 3 is plan view of my invention attached to a board, and Fig. 4 is a detail view of a detachable member.

25 Referring in detail to the drawings, 10 indicates a tubular foundation bar of a substantially rectangular shape having its end pieces perforated at evenly spaced intervals, as at 11. Two preferably angular shaped clutches 12, 12 are adapted to movably slide on said bar in order to clasp and retain the usual forms by exerting a pressure on the cleats 13. Said clutches are tightly adjusted to the forms by means of a detachable 30 key 14, and kept in the adjusted position by the pins 15.

The foundation bar has at each end a stop screw 16 to prevent said clutches from sliding off and getting lost when not in use.

40 At its center said bar has a handle-formed attachment 17 integrally fastened to said bar by means of two screws 18, the end pieces of which are slightly protruding at the opposite side of the bar, as at 19, in order to provide what may be termed seats for the board or form.

45 The said attachment and the bar have each a centrally located perforation 31, corresponding with one another, through which is inserted a screw bolt 20, said screw bolt has its lower end terminated into an eyelet 21, while its upper threaded part 22 is adapted to be screwed into a clip 23 for a purpose hereinafter more fully described.

50 The said bolt is intermitting the handle-attachment and the bar provided with a slid-

able bushing 24, said bushing has at one side a set screw 25, the inner end of which is adapted to fit slight depressions 26 made in said screw bolt at intervals.

55 A clip, preferably of the shape shown at 23, is made from a thin piece of metal, and is mounted by means of a screw-threaded engagement on said screw-bolt 20.

A downward projection 29 upon said clip 60 serves to tightly hold the board or form 30; in order, however, to accomplish this more fully said clip has projecting downwardly two screws or thin bars 28 of even length and flush with the projection 29, thus providing a strong grip on such board or form.

65 The aforesaid clip has upwardly projecting flanges 32 adapted to be bent upon the lower horizontal part of an I beam 33, as shown in Fig. 1.

70 If, however, said clip is applied to a one-side-flanged beam, as illustrated in Fig. 2 the flange of the said clip facing said straight sided flangeless beam is provided with holes 34 for the purpose of attaching 75 thereto wires 35, bent around the top of said beam as shown, and which in this case provide a solid attachment to said beam for said one side of a clip as shown clearly at 35.

75 The eyelet 21 of the bolt may be used as a support for scaffold bangers, as shown at 80; and it may likewise be employed for stripping, as shown at 37, for which latter purpose I use a telescopic member as shown at 38, providing a handle attachment for engagement with said eyelet 21, the handle terminating in an upwardly extending projection 39 to secure a solid engagement.

85 It is obvious that changes may be made in the form, construction and arrangement of the several parts, as shown, within the scope of the appended claims, without departing from the spirit of the invention, and I do not therefore limit myself to the construction and arrangement shown and described herein.

90 What I claim as new, and desire to secure by Letters Patent of the United States, is:

95 1. An article of manufacture comprising a rectangular bar, clutches slidably engaging said bar and means for adjusting the former; a screw-bolt inserted through a handle, rigidly attached to said bar, and through the latter, and means for adjusting 100 said screw-bolt, a clip mounted on said screw-bolt and adapted to retain an inserted

member in conjunction with said bar, substantially as shown and described.

2. An article as described, comprising a foundation bar having a plurality of apertures sidewise spaced and adapted to engage with a pin to retain in adjusted position a couple of clutches slidably mounted on said bar; a handle attachment below said bar, a screw-bolt turnably inserted through said handle and said bar and engaging by means of correspondingly threaded sections the lower body of a substantially U shaped clip; the latter having upwardly extending arms, one of these being perforated to receive wire strings, said arms adapted to clasp and retain a beam, while said clip at its bottom is provided with two downwardly projecting bars forming a flush horizontal surface with an intermittent embossment on said clip, for the purpose of securely retaining a board between said clip and bar.

3. A device for hanging forms from

structural steel beams, comprising a rectangular bar, retaining clutches slidably mounted on said bar and means for adjusting the former; a screw bolt turnable in said bar and in a handle rigidly secured to the latter at its bottom; a bushing mounted on said bolt between said bar and handle, said bushing being provided with a set screw adapted to fit depressions in set bolt for the purpose of securing a rigid attachment of the latter; screws inserted through said handle and forming small projections or seats on the upper surface of the bar, a U-shaped clip threaded upon the extreme end of said screw-bolt for operation in conjunction with said bar, the other end of said screw-bolt being provided with an eyelet for various purposes, substantially as shown and described.

In testimony of which I have hereunto affixed my signature.

OSKAR OLSEN.
